WHITE PRINT MACHINE

Joel W. Bravo, Montrose, Pa., assignor to GAF
Corporation, a corporation of Delaware

Filed Oct. 21, 1966, Ser. No. 4,361

Term of patent 7 years

(Cl. D61—1)

Fig. 1.

Fig. 2.

Fig. 3.

Fig. 4.

FIG. 1 is a front perspective view of a white print machine showing my new design;

FIG. 2 is a front elevational view thereof;

FIG. 3 is a left side elevational view thereof; and

FIG. 4 is a rear elevational view thereof.

The base, not shown, is conventional, and the side opposite that shown is substantially the same as the side which is shown.

I claim:

The ornamental design for a white print machine, substantially as shown and described.
